UNITED STATES PATENT OFFICE.

CLINTON B. REPP, OF NEW YORK, N. Y., ASSIGNOR TO CATHERINE M. M. VAHJEN,
OF BROOKLYN, NEW YORK.

COMBINED SEWING-MACHINE AND STAND.

No. 872,848.

Specification of Letters Patent.

Patented Dec. 3, 1907.

Application filed March 30, 1907. Serial No. 365,537.

To all whom it may concern:

Be it known that I, CLINTON B. REPP, a citizen of the United States, residing in New York, in the borough of Manhattan, county 5 and State of New York, have invented certain new and useful Improvements in Combined Sewing-Machines and Stands, of which the following is a specification.

This invention relates to a combined sewing-machine and stand, in which the sewing-machine can be operated when supported on the stand, by foot-power, and, when removed therefrom, as a hand-machine, as desired.

Smaller sized sewing-machines met with 15 considerable favor with the general public as an introduction to the use of the normally-sized sewing-machine. They were less attractive, however, for the reason that no stands were supplied for the same, so that 20 they could be operated by foot-power, which is necessary to produce a perfect simulation of a large-size sewing-machine.

For this purpose the invention consists of a sewing-machine which is provided with a 25 base-plate and combined with a knock-down stand consisting of a forked upright standard attached to one end of the base-plate, an inclined standard attached to the other end of the base-plate, and a brace-rod connecting 30 the lower ends of the forked and inclined standards.

The invention consists further of certain 35 details of construction which will be fully described hereinafter and finally pointed out in the claims.

In the accompanying drawings, Figure 1 represents a side-elevation of my improved combined sewing-machine and stand, Fig. 2 is an end-elevation of the same, showing the 40 treadle and fly-wheel, Fig. 3 is a horizontal section on line 3, 3, Fig. 1, showing the base-plate of the sewing-machine drawn on a larger scale, Fig. 4 is a detail-section, showing the application of a hand-crank to the sewing-45 machine when it is desired to run the same by hand.

Similar letters of reference indicate corresponding parts throughout the several figures.

Referring to the drawings, A represents a 50 sewing-machine of a smaller size, which is made preferably of the Wilcox & Gibbs type for making the chain-stitch. The sewing-machine is provided with a feed, a stitch-regulator, a tension-device for the thread, 55 and other well-known accessories.

The frame *a* of the sewing-machine is provided at its lower part with a horizontal base-plate *b*, which is preferably cast integral with the frame *a* of the sewing-machine, the base-plate being of circular shape at its middle 60 portion where it connects with the frame of the sewing-machine, and provided at its opposite ends, in line with the center of the uprights of the sewing-machine frame, with the narrow extensions *c*, *c*, of different 65 lengths. The longer lug *c* is provided at its outer end with an upwardly-extending rectangular lug or shoulder *d*.

The base-plate *b* is of sufficient strength to support the sewing-machine and also form 70 the support for the upper part of a so-called knock-down stand, which is composed of three parts, a forked upright main-standard *g* which is connected at the lower part by a transverse brace *g*¹, made integral with the 75 standard *g* and near its middle part by a transverse brace *g*² both braces being perforated as shown in Fig. 2. The upper end of the standard *g* is provided with an inwardly-projecting shoulder *i* on which the shoulered end of the base-plate *b* is supported, as 80 shown in Fig. 1. The upper end of the forked standard *g* is attached by a screw *h* to the shoulered end of the base-plate, so that the same rests firmly on the inwardly-projecting shoulder *i* of the same. To the opposite extension *c* of the base-plate *b* is attached 85 the upper lug-shaped end *f*¹ of an inclined standard *f* which has an obtusely-angled bend *f*² at its lower end, and which is connected by a horizontal brace-rod *f*³ with the strengthening brace *g*¹ at the lower end of the forked main-standard, said rod being bent at its ends and attached by fastening-screws *s* to the inclined standard *f* and to the transverse brace of the forked main-standard *g*, as 90 shown in Figs. 1 and 2.

To the horizontal rod *f*³ is pivoted a treadle *t* which is provided with an extension-lever *t*¹ to the outer end of which is applied a pitman *p* which is pivoted to the arm *t*¹ and to one of the spokes of a fly-wheel *w*. The fly-wheel *w* turns in bearings of a stud-shaft on the transverse brace *g*² of the forked main-standard, as shown in Fig. 1 and Fig. 2. The 105 motion of the fly-wheel *w* is transmitted by a belt or cord *o* to a pulley or driven-wheel *o*¹ on the shaft *m* of the sewing-machine, so that the latter can be operated by working the treadle by the foot in the same manner as 110

ordinary large-sized sewing-machines. One of the spokes of the pulley or driven-wheel o^1 on the shaft m of the sewing-machine operates the needle-bar of the machine by means 5 of a connecting-rod o^2 in the usual manner, while the stitch-forming parts of the sewing-machine, the feed, regulator, etc., are operated from the shaft m in any approved manner.

- 10 The supporting-stand is made up of two separable standards g and f which are screwed to the base-plate and to the connecting-rod when the sewing-machine is to be mounted thereon. By unscrewing the various connecting-screws the stand may be detached 15 from the base-plate of the sewing-machine, and thereby conveniently packed, together with the treadle, pitman and fly-wheel, in a small box separate from the sewing-machine. When it is desired to mount the machine on the stand, the parts are easily placed in position according to printed instructions, so that the small-sized sewing-machine can be used in the same manner as a 20 large-sized machine by foot-power, and thereby not only greater enjoyment obtained in running the same, but also better and more effective work as the use of the hand for operating the crank of the sewing-machine is dispensed with and thereby both 25 hands are available for sewing.

When the sewing-machine is to be run as a foot-power machine, the hand-crank e is removed, but when it is desired to use it as a 30 hand-operated machine then the screw-pivot x by which the connecting rod o^2 is applied to the pulley or driven-wheel o^1 is removed and the hand-crank screwed thereon, as shown in Fig. 5. In this case the sewing-machine can be used as a hand-machine, either on the stand, or detached from the 35 same, in the same manner as the well known small-sized toy sewing-machines.

The combined sewing-machine and stand 40 has the advantage that it can be operated either by hand or by foot, whereby the running of the machine gives greater pleasure to the user, while owing to the simplicity of

the construction of the sewing-machine and its stand, they can be furnished at a very 50 low price, so as to be within the reach of nearly every one, especially as the work done by the machine is about the same as that done on a large-sized and more expensive machine. 55

Having thus described my invention, I claim as new and desire to secure by Letters Patent:

1. The combination, with a sewing-machine provided with a base-plate at the lower part of its frame, of a knock-down supporting-stand for the same consisting of a forked and braced main-standard attached to one end of the base-plate, an inclined standard attached to the opposite end of the base-plate, a bottom brace-rod connecting the lower ends of the main and inclined standards, means for connecting the base-plate with the upper ends of the main and inclined standards, and means for connecting the lower ends of the standards with the bottom-brace-rod. 60

2. The combination, with a sewing-machine provided with a base-plate at the lower end of its frame, said base-plate having an extension with an upwardly-extending lug, of a knock-down supporting-stand consisting of a forked and braced main-standard provided with a shoulder at its upper end for the extension of said base-plate, 65 an inclined standard attached to the opposite end of the base-plate, a bottom brace-rod connecting the lower ends of the main and inclined standards, and means for attaching the upper ends of the forked main 70 and inclined standards to the opposite ends of the base-plate and the lower ends of the same to the bottom brace-rod. 75

In testimony, that I claim the foregoing as my invention, I have signed my name in 80 presence of two subscribing witnesses.

CLINTON B. REPP
